WATER HEATER

James T. Barrow, New York, N. Y.

Application June 18, 1934, Serial No. 731,214

12 Claims. (Cl. 257—248)

My invention relates to water heating systems and has particular reference to systems employing heat exchangers for heating water by steam from heating boilers, employing also separate water heating containers in boiler furnaces.

This is continuation in part of my application Serial No. 700,300, filed Nov. 29, 1933.

The object of my invention is to provide means for heating a limited amount of water in a separate heating unit or element supported in the boiler furnace, this water to be used for household purposes. Another object of my invention is to provide a convenient water heating element which can be assembled in the furnace of a house heating boiler without taking the furnace apart for introducing this element. Still another object of my invention is to provide means for varying connections between this special container, boiler, heat exchanger, and the tank for hot water, in accordance with seasonal requirements of service. For this purpose I provide a double two-way valve with which the proper connections are made by the single turn of its handle. This valve is more specifically described in my copending application Serial No. 700,300, filed Nov. 29, 1933. I also provide a special water heating element composed of two parts which can be fitted or assembled together inside of the boiler furnace. The individual parts of the element are sufficiently small to be inserted through the ordinary door of the furnace, and the unit can be then assembled inside of the furnace above the burner. The other features of my system are similar to those described in my Patent No. 1,958,736.

My invention is more fully described in the accompanying specification and drawings in which—

Fig. 1 is a sectional elevation of a boiler with my heating system, Fig. 2 is a sectional view of my heating element, Fig. 3 is a top view of the same partly in section, Fig. 4 is a side view of one component part of the element, Fig. 5 is a side view of the heating element partly in section taken on the line 5—5 of Fig. 3, Fig. 6 is a top view of one component part of the element, Fig. 7 is a detail view of the closing plate, Fig. 8 is a top view of a modified device partly in section, Fig. 9 is a side view of one portion of the same, Fig. 10 is a side view of the element, Fig. 11 is a partial sectional view of another modification of the heating element, Fig. 12 is a partial side view of this modification, and Fig. 13 is a partial sectional view of another modification.

My water heating system comprises a boiler

1 with an oil burner 2 in a furnace 3. A pipe 4 extends from the water gauge 5 in the upper portion of the boiler to an outer shell 6 of a heat exchanger. The lower portion of the shell is connected by a pipe 7 with the lower portion of the boiler and with a pipe 8 which supplies water for the house heating system. A steam pipe 9 connects the top of the boiler with the pipe 4. The pipe 4 also connects with a double two-way valve 11 by a pipe 10. The same side of the valve 11 is connected by a pipe 12 with the pipe 7. The valve has a handle 13 for turning it thereby changing connections between different pipes connected with it. The other side of the valve 11 is connected by pipes 14 and 15 with a circular heating element or container 16 for water. This container is supported on legs 17 above the burner 2 and is heated by the same.

The container consists of two symmetrical semicircular portions provided with angular lugs 18 and 18' made so that the smaller lugs 18 fit inside of the lugs 18'. The ends of the container halves are milled down and provided with tapering sides 19 into which fit cover plates 20. Bolts 21 tighten the plates against the joined lugs. The tapers on the plates, acting on the tapered portions on the ends of the halves, draw them apart thereby tightening the joints between the angular portions of the lugs. Gaskets 22 are provided for rendering the joints water tight. One of the plates at one end has a hole 14' for the pipe 14, and one of the plates at the other end has a hole 15' for the pipe 15. The hollow semicircular members 16 are of such size that they can be inserted in the furnace through its front door 23. The plates 20 may be previously screwed on the ends of the pipes 14 and 15. The members 16 are then fitted together by sliding the interlocking lugs 18 and 18' over each other. The free plates 20 are then placed on the joints with the gaskets 22, the gaskets being also placed under the plates 20 on the pipe ends. The plates are then drawn together by the bolts 21 tightly clamping the joints. The spreading action of the tapered ends of the plates engaging the tapers 19 of the members 16 will tighten the lugs 18 and 18' together, forming hermetically sealed joints.

The valve 11 has ports opposite the pipes 10 and 15 connected with pipes 24 and 25 connected with a coil 26 of the heat exchanger inside of the housing 6. Pipes 27 and 28 extend from the pipes 24 and 25 to the top and bottom of a storage tank 29 for hot water.

A pipe 30 leads from the top of the tank to the supply system of the hot water for household

purposes. A pipe 31 serves to feed fresh water to the heating system, and a pipe 32 is used for draining the system. It is provided with a cock 33. A safety blow-off valve 34 is placed on the 5 pipe 14. An electric regulator 35 of an ordinary construction is placed on the pipe 4 and may be connected with the burner 2 for regulating the temperature of the boiler water. Any ordinary 10 temperature control may be used for this purpose, as well as a manual control.

The operation of my system is as follows.

During the winter, when the boiler 1 is being operated for heating the house, water in the 15 tank 29 is heated by the heat exchanger through which circulates the hot boiler water, heating the coil 26. Hot water rises to the top of the tank through the pipe 27, and the cold water is fed into the coil through the pipe 28 from the bottom of the tank. The circulation continues until the 20 heat balance is established. The valve handle 13 is turned to the left disconnecting the coil 26 from the heating member 16. The latter is then connected through the pipes 14 and 15 with the boiler 1, the pipes 10 and 12 being connected in the 25 valve with the pipes 14 and 15. Water in the heating element circulates through the boiler thereby forming a supplementary supply of hot water for the boiler. The heating element in this 30 case increases the boiler capacity by adding to its heating surface and volume of water, at the same time utilizing more efficiently the heat of the burner. Water for household purposes is heated indirectly from the boiler through the heat exchanger.

35 In summer when the boiler is not used, the valve handle 13 is turned to the right, disconnecting the pipes 10 and 12 and connecting the pipes 14 and 15 with the pipes 24 and 25 respectively. With these connections the heating 40 element heats directly water in the tank. Water circulates through the pipes 28 and 15 from the tank into the heating element, and through the pipes 14 and 27 from the heating element into the tank. Hot water from the heating element 45 also circulates through the coil 26 thereby heating the water in the heat exchanger shell 6. The heated water enters the boiler through the pipe 4, cold water from the boiler entering the shell through the pipe 7. The boiler water thereby 50 gradually becomes heated and serves as an additional supply of hot water for household purposes, or it may be used to heat the tank water through the heat exchanger, if the burner is temporarily extinguished.

55 A modified construction of the water heating element or container is shown in Figs. 8, 9 and 10. It consists of two symmetrical halves 36 provided with pipe nipples 37 for connecting the element with the pipes 14 and 15. The halves have bosses 38 inside drilled for bolts 39. Corresponding bosses 40 are provided on the outside for the bolts. While the unit is circular in its general shape, the inner sides are flattened as shown in order to 60 compensate for the space used for the inner bosses 38 and to provide thereby a constant area inside for the circulation of water. Gaskets 41 form water tight joints. This construction has an advantage that the bolts do not come in contact with water.

Another modification is shown in Figs. 11 and 65 12. The two halves 42 have their ends tapering at an angle and are joined by bolts 42 passing transversely through the sides of the halves at their ends. Bosses 44 are provided inside being drilled for the bolts in order to keep the bolts

from contact with water. Gaskets 45 render the joints water tight. Lugs 46 are provided on the sharp ends overlapping the blunt ends of the halves in order to keep the sides from creeping or sliding transversely under pressure from the bolts.

Important advantages of my system are that it can be installed in any existing boiler used for household heating, also that it increases the boiler capacity and its heating surface. It permits the use of the burner of the boiler in the summer for obtaining hot water for household purposes when the boiler is not used for heating the house. My heating element has an advantage that it is made of two halves which can be 15 inserted into the boiler furnace through its door and assembled inside of the furnace into the complete heating unit, so that the whole installation can be made for the boilers already installed and in operation.

The transverse bolts 43 can be placed at an angle with the halves 42 of the water heater as shown in Fig. 13. In that case the lugs 46 may be entirely omitted.

I claim as my invention:

1. A heating element for a water heating system, comprising two hollow semicircular members, angular lugs on the ends of said members, the lugs on one end of each member being smaller than the lugs on the other end, the larger lugs 30 being adapted to slidably fit over the smaller lugs, thereby joining together said members into a ring-shaped container with an annular chamber inside, closing members for the sides of said ring at the joints formed by said lugs, means to 35 tighten said closing members against said joints thereby rendering said joints leakproof, means for supporting said heating element inside of the furnace of a boiler above the burner of said furnace, and an inlet and an outlet in said container for connection with water pipes.

2. A heating element for a water heating system, comprising two hollow members open at their ends, angular lugs on the ends of said members, the lugs of one of said members slidably 45 engaging the corresponding lugs of another member, sealing members for the joints formed by said lugs, bolts clamping said sealing members against said joints thereby rendering said joints waterproof, said members being adapted to be 50 assembled inside of the furnace of a boiler, forming a ring-shaped container for water, means to support said container in said furnace, and an inlet and an outlet in said container for connection with water pipes.

3. A heating element for a water heating system, comprising two hollow members open at their ends, mutually interlocking lugs on the ends of said members, means to close the joints formed by said lugs and to tighten said lugs 60 against each other thereby rendering said joints waterproof, said members with said joints forming a ring-shaped container for water, means for supporting said container inside of a furnace of a boiler, and an inlet and an outlet in said 65 container for connection with water pipes.

4. A heating element for a water heating system, comprising two hollow members open at their ends, lugs on the ends of said members, the lugs on one end of each member being larger 70 than on the other end, the small lugs of one member being slidably engaged by the large lugs of the other member by sliding in direction perpendicular to the plane of said members, said members with the lugs thus engaged forming 75

- 5 a container for water, closing plates for the sides of said lugs, bolts for tightening said plates against said lugs thereby rendering the joints between said members waterproof, means for supporting said elements inside of the furnace of a boiler, and an inlet and an outlet in said container for connection with water pipes.
- 10 5. A heating element for a water heating system, comprising two hollow members open at their ends, lugs on the ends of said members, said lugs on one end of each member being smaller than the lugs on the other end, the larger lugs being adapted to partly enclose the smaller lugs, said larger lugs being adapted to slide over said 15 smaller lugs in direction perpendicular to the plane of said members, said members with the lugs mutually engaged forming a hollow closed container for water, plates fitting over the sides of said lugs, said plates being provided with tapered edges, said members being provided with 20 tapered shoulders at their ends back of said lugs, said plates being adapted to fit said shoulders by the tapered edges, bolts adapted to draw said plates against the sides of said lugs, said plates being adapted to spread said members apart by 25 said tapered edges thereby tightening the outer edges of the larger lugs against the inner sides of the smaller lugs, said members with their lugs mutually engaged and with said plates and bolts 30 assembled forming a hollow enclosed container for water, means for supporting said container inside of the furnace of a boiler, and an inlet and an outlet in said container for connection with water pipes.
- 35 6. A heating element for a water heating system, comprising two hollow semicircular members open at their ends, said ends being shaped to fit together so as to form watertight joints, said members being adapted to be assembled together inside 40 of a boiler furnace forming a ring-shaped container for water, bolts connecting together said members and passing through the water space in said container, bosses inside of said members for protecting said bolts from contact with the water 45 inside of said container.
- 50 7. A water heating element for a water heating system, comprising two semicircular hollow members open at their ends, said ends being fitted together so as to form watertight joints, bolts adapted to join said members and passing through the inside space in said members, bosses for said bolts inside of said members for protecting said bolts from contact with water inside, and bosses on the outside for the heads of said bolts, said members being adapted to be assembled inside of a boiler 55 furnace.
- 55 8. A water heating element for a water heating system, comprising two semicircular hollow members open at their ends, bolts passing through said ends and connecting said members together, said bolts passing through the inside space in said members, said ends being fitted together so as to form watertight joints, bosses inside protecting said bolts from contact with the water inside, the walls of said members at their ends being shaped to avoid diminishing the internal cross-sectional area of the passage through the members.
- 10 9. A water heating element for a water heating system comprising, two semicircular hollow members open at their ends, bolts passing through said ends transversely to the plane of said members, said members forming a ring-shaped container for water adapted to be assembled inside of a boiler furnace, the ends of said members being formed at an angle with said bolts and adapted to form watertight joints, and means to prevent mutual sliding of said ends when tightened 15 together by said bolts.
- 15 10. A water heating element for a water heating system, comprising two hollow members open at their ends, the ends of one member being shaped to fit the ends of the other member, bolts 20 passing through said ends in a direction substantially transverse to the plane of said element and through the water space in said members, bosses inside of said members totally enclosing said 25 bolts, and means to render the joints between said members leak-proof, said members when joined 30 by said bolts forming a ring-shaped container.
- 35 11. A water heating element for a water heating system, comprising two hollow members open at their ends, the ends of one member abutting the ends of the other member, the planes of abutment being at an angle with the plane of said members, bolts to join together said members at their ends and passing through said ends and 40 through the water space in said members at an angle to the planes of abutment, and means to render the joints between said members leak-proof, said members when connected by said bolts 45 forming a ring-shaped container.
- 45 12. A water heater, comprising two hollow semicircular members open at their ends, said ends being fitted together so as to form watertight joints, said members being adapted to be assembled together inside of a boiler furnace 50 forming a ring-shaped container for water, means to support said container in said furnace, bolts connecting together said members, said bolts passing through the water space in said container, and an inlet and an outlet for said container.

JAMES T. BARROW.
